UNITED STATES PATENT OFFICE.

HERMAN ABRAMS, OF PHILADELPHIA, PENNSYLVANIA, ASSIGNOR TO CRESCENT BRASS MFG. COMPANY, OF READING, PENNSYLVANIA, A CORPORATION OF PENNSYLVANIA.

DESIGN FOR A CANDLE CUP FOR LIGHTING FIXTURES.

Application filed December 29, 1927. Serial No. 24,690. Term of patent 7 years.

To all whom it may concern:

Be it known that I, HERMAN ABRAMS, a citizen of the United States, residing at Philadelphia, in the county of Philadelphia and State of Pennsylvania, have invented a new, original, and ornamental Design for a Candle Cup for Lighting Fixtures, of which the following is a specification, reference being had to the accompanying drawing, forming part hereof, in which—

Fig. 1 is a side elevation;

Fig. 2 is a bottom view showing my new design.

I claim:

The ornamental design for a candle cup for lighting fixtures, as shown.

HERMAN ABRAMS.
